UNITED STATES PATENT OFFICE.

CAMILLE MAUBORGNE, OF MONTREAL EAST, QUEBEC, CANADA, ASSIGNOR TO ALARM
LOCK COMPANY LIMITED, OF MONTREAL, CANADA.

SAFETY DEVICE FOR AUTOMOBILES.

Application filed May 28, 1925. Serial No. 33,579.

The present invention pertains to a safety device for automobiles designed to prevent unauthorized access to the parts which must be actuated in order to move the vehicle.

The particular object of the invention is the provision of a device of this character including a secondary two-way switch contained in a housing having a locked door. The terminals of the switch are connected to the ignition system and to an alarm device. The apparatus is so constructed that the switch may be actuated from the exterior of the housing to break the ignition circuit, but the door must be unlocked in order to permit access to this switch for again making the circuit. This switch is secondary to a main two-way switch which is so connected that by movement of the switch arm thereof a circuit may be completed to the ignition system through the usual key switch on the dash board. In another position, the main switch makes a circuit through the arm of the secondary switch, requiring and enabling control through the secondary switch in the manner already stated.

A further feature of the invention is the provision of a circuit adapted to pass through the lock to the alarm device. In this circuit is interposed a circuit maker which operates if the lock is tampered with when the proper combination of the lock is not set. By operation of this contrivance, the alarm continues to operate until the lock is opened by some one who is familiar with the combination.

The housing also contains a pair of switches controlling circuits operating electro-magnetic locks for the sections of the hood. These switches are accessible only from the interior of the housing so that the motor cannot be uncovered unless the door of the housing is opened.

The invention is fully disclosed in the following description and in the accompanying drawings in which:

Figure 1 is an inside elevation of the lock showing the bolt projected,

Figure 2 is a similar view showing the bolt withdrawn,

Figure 3 is an outside elevation of the switch panel,

Figure 4 is a section on the line 4-4 of Figure 5, showing the lock in elevation,

Figure 5 is a section on the line 5-5 of Figure 4,

Figure 6 is a longitudinal section through the disc arbour and associated parts,

Figure 7 is a transverse section of the device showing the parts in the same position as in Figure 1,

Figure 8 is a fragmentary elevation of the lock, showing the theft alarm circuit closed,

Figure 9 is a detail transverse section showing the position of parts and the theft alarm circuit is open,

Figure 10 is a similar section showing the position of parts when the theft alarm circuit is closed,

Figure 11 is a section on the line 11-11 of Figure 8,

Figure 12 is a section on the line 12-12 of Figure 8,

Figure 13 is a longitudinal section showing the inner side of the switch panel,

Figure 14 is an outside elevation, and

Figure 15 is a detail section of the panel.

Reference to these views will now be made by use of like characters which are employed to designate corresponding parts throughout.

The device consists of a housing 1 (Figure 7) having an open side and an outwardly extending flange 2 formed along the edges of this side. Against the flange is placed a substantially rectangular frame 3, and over this is disposed a similar cover plate 4 containing a cover 5 attached to the plate by means of hinges 6. A pair of lateral members 7 secured to the underside of the cover plate support a switch panel 8 of insulating material as clearly shown in Figures 5 and 7.

The inner face of the panel (Figure 13) carries a main two-way switch consisting of contacts 9 and 10 and a pivoted switch arm 11 adapted to engage either one of these contacts independently. The outer face of the panel (Figure 3) supports another or secondary two-way switch consisting of a pair of bifurcated terminals or clips 12 and 13 between which is pivoted a switch blade 14 on a post 15. The terminals 9 and 10 extend through the panel as may be seen from Figures 3 and 13. At the outer face of the panel, the terminal 9 has secured thereto a conductor 16 extending to the usual ignition switch on the dash board. Thus, when this terminal is engaged by the switch arm 110

105

11, the ignition system may be set in operation by means of the usual key on the dashboard.

At the outer face of the panel, a conductor 17 leads from battery through terminal 10 to the post 15. Still another conductor 18 extends from the clip 13 to the ignition system. When the switch arm 11 engages the terminal 10 and the plate 14 is inserted in the clip 13, the ignition system is set into operation through the circuit made by these connections.

The locking device carried by the cover 5 includes an arbour 19 passed therethrough. 15 The outer end of the arbour carries a knurled knob 20 and a bevelled dial 21 which engages the cover as clearly shown in Figure 6. On the inner end is mounted a head 22 held in place by a pin 23. The 20 head is formed with an integral flange 24, and this is engaged by a permutation disc 25 having a notch 26 in its edge. This disc is in some manner fixed to the shaft and may, if desired, be formed integral with the 25 flange 24. Another permutation disc 27 is loosely mounted on the shaft and spaced from the member 25 by means of a washer 28. The disc 27 also has a notch 29 in its edge adapted to coincide with the notch 26 30 as may be seen in Figures 1 and 2. Fixed to the disc 27 is a cam or toothed member 30 for a purpose pointed out below. This member is engaged by washer 31, and between this member and the inner face of the 35 cover 5 is a broken washer 32.

To the inner face of the cover is pivoted a bar 33 on which is formed the bolt 34 of the lock. The lower edge 35 of the bolt is adapted for reception between the inner 40 face of the cover and the washer 31 which is permitted by reason of the broken washer 32. Over the bar 33 and bolt 34 is laid an angular arm 36 which is pivoted at 37 to the opposite edge of the cover. This member has a slot 38 between its ends, and in the slot is received a screw and nut device 39 which holds the arm and bolt firmly 45 against the cover. The bolt is likewise formed with a slot (not shown) also penetrated by the bolt and nut device thereby permitting movement of the bar 33 and associated parts.

The bar 33 is formed with a sheath 40 in which is contained a slidable tooth 41 (Figure 11). A transverse pin 42 carried by the tooth is adapted to move in slots 43 cut in the sides of the sheath. Adjacent the sheath an angle piece 44 is secured to the bar 33, insulated therefrom, and carries a binding post 45. This post is connected by means of a conductor 46 to another binding post 47 on the outer face of the panel and thence to a suitable alarm device (not shown) by means of another conductor 48. 60 The top 44' of the angle piece 44 is pro-

vided with a regulating screw 49. The free end of the arm 36 has attached thereto a spring conductor 50 which extends beneath the top 44' and is adapted for engagement by the stem 42 and screw 49. Adjacent the 70 sheath 40, a boss 51 is formed on the arm 36. This member contains a plunger 52 which is normally pressed outwardly by a spring 53. The outer end of the plunger has a notch 54 in which may be received the 75 stem 42 as illustrated in Figure 12 for the purpose pointed out below. The plunger has a knob 55 extending through the wall of the post and slidable therein, whereby it may be pushed inwardly when desired. 80

The free end of the arm 36 is formed as a pocket 56 which encloses one end of a rod 57 (Figure 1) rotatably mounted in the cover 5. The outer end of the rod is provided with an operating handle 58 as shown 85 in Figure 5. The permutation disc or tumblers have stops 59 on their opposed faces whereby the two notches may be brought into registration with one another beneath tooth 41 by operation of the knob 90 20 and dial 21 in a manner already known in the art. At this time the handle 58 is turned, causing the finger 60 at the inner end thereof to press downwardly on the lower edge 56' of the pocket 56 and thereby 95 swing the arm 36 downwardly on its pivot 37. The inner face of the arm is formed with a lug 61 adapted to engage the upper edge of the bar 33 so that the latter is already brought downwardly during this 100 movement to withdraw the bolt 34. To the inner face of the cover is pivoted a dog 62 adapted to enter notch 63 in the bolt when the latter reaches its final lower position. The dog is removed from the notch by turning the tooth 30 to the position shown in 105 Figure 1 when it is desired to project the bolt 34 for locking the door. The dog is normally held against the bolt by means of a spring 64 wound over a stud 65 on the 110 cover. The spring also enters the arm 36 above its pivot point and thereby tends to raise the latter. Another spring 66 is secured to the cover and engages the lower edge 56' of the pocket 56 and also aids in 115 the upward movement of the arm 36. This movement is arrested when the finger 60 on the rod 57 engages a stud 67 carried by the cover. Still another spring 68 acts on the pivoted end of the bar stem 33 and on the 120 finger 60.

The spring conductor 50 is grounded through the arm 36, cover 5, hinges 6, blade 4, lateral member 7, and finally through a wire 68 secured to the latter at the rear 125 face of the panel by means of a binding post 69. The conductor 70 extending from the upper clip 12 leads to a switch brake, of a well known type, which is closed when the brake is released, and thence to the 130

ground or return circuit of the alarm device mentioned above. In order that the switch 12-15 may be actuated from the exterior of the cover 5 when the same is 5 locked, a pair of stems 71 and 72 (Figure 13) extend from the switch blade through the panel 8. In the cover is mounted a spring-pressed push button 73 adapted to engage the lower stem 72 and thereby move 10 the blade out of the clip 13 and into the clip 12. The ignition circuit cannot again be closed by pressure on the stem 72 until the cover is opened.

The inner face of the panel 8 supports a 15 clip 82 which encloses, but does not engage, a finger 83 also supported by the panel. These members are secured to the panel by binding posts 84 and 85 respectively which extend to the outer face of the 20 panel as shown in Figures 3 and 15. The former post is connected to post 47 by a conductor 86 and the post 85 communicates with the switch pivot 15 through a conductor 87. The switch arm 11 carries a 25 blade 88, insulated therefrom, adapted to enter clip 82 and connect it to fingers 83 when the arm 11 engages the terminal 10, as illustrated in Figure 8. In this manner a circuit is made between the battery connection 17 and the alarm conductor 48 when 30 the arm 11 is brought into engagement with the terminal 10.

When the vehicle is to be parked, the 35 driver applies the brake, opening the brake switch, and then presses the button 73 to move the switch blade 14 out of the clip 13 and into the clip 12. Although the ignition circuit is thereby broken, a connection is 40 made between pivot post 15 and conductor 70. If the brake is now released in an attempt to steal the vehicle by towing, the 45 brake switch is closed whereby the pivot post 15 is grounded to conductor 70 and the switch brake. Current is tapped at post 15 flowing through conductor 17 to the 50 ground and through conductor 87, post 85, clip 82, finger 83, blade 88, post 84, conductor 86, post 47 and conductor 48 to the alarm device. Since the battery and alarm 55 are also grounded, the alarm will be actuated to indicate that the brake has been released.

The spring conductor 50 and connected 55 parts serve to operate the alarm device when the lock is tampered with. This condition is shown in Figure 8. Assuming that the permutation discs have not been set in proper combination, rotation of the handle 58 will cause the arm 36 to move downwardly in the manner already described. The tooth 41 will engage the edges of the disc and be stopped thereby and consequently cause the stem 42 to hold the free 60 end of the conductor 50. Upon continued 65 movement of the arm 37, the conductor will

be engaged by the screw 49. The circuit of the alarm device which is normally broken by the insulation of the angle piece 44 will then be closed through the conductor 48, angle piece, screw 49, conductor 50, and 70 ground wire 68. The stem 43 will be received in the notch 54 of the plunger 52 to make this connection permanent until the plunger is withdrawn by pressure on the stem 55. It will be noted that the latter 75 movement cannot be made until the cover is opened, whereby the alarm continues to operate until such time.

To the outer face of the panel 8 is secured a pair of spring arms 74 (Figure 3) having 80 binding posts 75 attached thereto. The binding posts are connected by conductors 76 to the electro-magnetic locks adapted to hold in closed position the hood sections of the vehicle (not shown). The arms 74 pass 85 beneath a conducting strip 77 to which is also attached the arm 11 of the main switch. The spring arms are normally spaced from the strip, but may be moved into engagement therewith by pressure on buttons 78 of 90 the insulating material carried by the members 74 and accessible from the inner side of the panel. By operation of these buttons which can be reached only when the door 5 is open, a circuit may be completed to either 95 one of the electro-magnetic locks.

In order to throw the door open when the bolt 34 is withdrawn, there is mounted on the inner side of the panel a sleeve 79 containing a spring 80. A plunger 81 is slidably disposed in the sleeve, having one end in engagement with the spring and the other end engaging the inner face of the door. When the door is closed, as in Figure 5, the spring is under pressure. Therefore, 100 when the bolt is withdrawn, the door is thrown open by virtue of this pressure.

It should be noted that unless the permutation discs are set in a locking position 105 it is impossible to close the door, thereby 110 protecting the owner against forgetting to properly protect his vehicle.

While a specific embodiment of the invention has been illustrated and described, it is to be understood that various alterations in the details of construction may be made without departing from the spirit of the invention as indicated by the appended 115 claims.

Having thus fully described the invention, 120 what I claim as new and desire to protect by Letters Patent is:—

1. A safety device for automobiles comprising a housing having a movable door and a lock carried by said door, a main two-way switch and a secondary two-way switch mounted in said housing, each switch including a pair of terminals and a switch arm, one of the terminals of the main switch being connected to the arm of the secondary 125 130

4
switch, the remaining terminal of the main switch being adapted for connection to a dash board switch, and the terminals of the secondary switch to the alarm and ignition systems of the vehicle.

2. A safety device for automobiles comprising a housing having a movable door and a lock carried by said door, a main two-way switch and a secondary two-way switch mounted in said housing, each switch including a pair of terminals and a switch arm, one of the terminals of the main switch being connected to the arm of the secondary switch, the remaining terminal of the main switch being adapted for connection to a dash board switch, and the terminals of the secondary switch to the alarm and ignition systems of the vehicle, and means disposed exteriorly of the housing for actuating said secondary switch.

25 3. A safety device for automobiles comprising a housing having a movable door and a lock carried by said door, a main two-way switch and a secondary two-way switch mounted in said housing, each switch including a pair of terminals and a switch arm, one of the terminals of the main switch being connected to the arm of the secondary switch, the remaining terminal of the main switch being adapted for connection to a dash board switch, and the terminals of the secondary switch to the alarm and ignition systems of the vehicle, a pair of operating stems extending from the arms of the secondary switch, and means disposed exteriorly of said housing for engaging one of said stems.

40 4. A safety device for automobiles comprising a housing having a movable door, a plurality of notched permutation discs of said door, an arm pivoted to said door, a locking bolt upwardly connected to said arm, a slidable tooth carried by said arm, said tooth being receivable in the notches of the discs and adapted to engage the edges of the discs, a circuit maker carried by the arm and operable by said tooth, a main two-way switch and a secondary two-way switch mounted in said housing, each switch including a pair of terminals and a switch arm, one of the terminals of the main switch being connected to the arm of the secondary switch, the remaining terminal of the main switch being adapted for connection to a dash board switch, and the terminals of the secondary switch to the alarm and ignition systems of the vehicle.

45 5. A safety device for automobiles comprising a housing having a movable door, a plurality of notched permutation discs of said door, an arm pivoted to said door, a locking bolt upwardly connected to said arm, a slidable tooth carried by said arm, said tooth being receivable in the notches of the discs and adapted to engage the edges

of the discs, a circuit maker carried by the arm and operable by said tooth, a main two-way switch and a secondary two-way switch mounted in said housing, each switch including a pair of terminals and a switch arm, one of the terminals of the main switch being connected to the arm of the secondary switch, the remaining terminal of the main switch being adapted for connection to a dash board switch, and the terminals of the secondary switch to the alarm and ignition systems of the vehicle, and means disposed exteriorly of the housing for actuating said secondary switch.

20 6. A safety device for automobiles comprising a housing having a movable door, a plurality of notched permutation discs of said door, an arm pivoted to said door, a locking bolt upwardly connected to said arm, a slidable tooth carried by said arm, said tooth being receivable in the notches of the discs and adapted to engage the edges of the discs, a circuit maker carried by the arm and operable by said tooth, a main two-way switch and a secondary two-way switch mounted in said housing, each switch including a pair of terminals and a switch arm, one of the terminals of the main switch being connected to the arm of the secondary switch, the remaining terminal of the main switch being adapted for connection to a dash board switch, and the terminals of the secondary switch to the alarm and ignition systems of the vehicle, a pair of operating stems extending from the arms of the secondary switch, and means disposed exteriorly of said housing for engaging one of said stems.

25 7. A safety device for automobiles comprising a housing having a movable door, a plurality of notched permutation discs carried by said door, an arm pivoted to the door, a locking bolt operably connected to said arm, a slidable tooth carried by said arm, said tooth being receivable in the notches of the discs and adapted to engage the edges of the discs, opposite lines of a circuit connected to said arm, a conducting piece attached to one of said lines and insulated from said arm a conducting strip secured to said arm and normally spaced from said piece a stem carried by the tooth and adapted to bring said strip into engagement with said piece, a main two-way switch and a secondary two-way switch mounted in said housing, each switch including a pair of terminals and a switch arm, one of the terminals of the main switch being connected to the arm of the secondary switch, the remaining terminal of the main switch being adapted for connection to a dash board switch, and the terminals of the secondary switch to the alarm and ignition systems of the vehicle.

8. A safety device for automobiles com-

- prising a housing having a movable door, a plurality of notched permutation discs carried by said door, an arm pivoted to the door, a locking bolt operably connected to said arm, a slideable tooth carried by said arm, said tooth being receivable in the notches of the discs and adapted to engage the edges of the discs, opposite lines of a circuit connected to said arm, a conducting piece attached to one of said lines and insulated from said arm a conducting strip secured to said arm and normally spaced from said piece a stem carried by the tooth and adapted to bring said strip into engagement with said piece, means carried by said arm for retaining said strip in engagement with the angle piece, a main two-way switch and a secondary two-way switch mounted in said housing, each switch including a pair of terminals and a switch arm, one of the terminals of the main switch being connected to the arm of the secondary switch, the remaining terminal of the main switch being adapted for connection to a dash board switch, and the terminals of the secondary switch to the alarm and ignition systems of the vehicle. 70
- 10 piece attached to one of said lines and insulated from said arm a conducting strip secured to said arm and normally spaced from said piece a stem carried by the tooth and adapted to bring said strip into engagement with said piece, a main two way switch and a secondary two-way switch mounted in said housing, each switch including a pair of terminals and a switch arm, one of the terminals of the main switch being connected to the arm of the secondary switch, 75
- 15 engagement with said piece, a main two way switch and a secondary two-way switch mounted in said housing, each switch including a pair of terminals and a switch arm, one of the terminals of the main switch being connected to the arm of the secondary switch, 80
- 20 switch being connected to the arm of the secondary switch, the remaining terminal of the main switch being adapted for connection to a dash board switch, and the terminals of the secondary switch to the alarm and ignition 85
- 25 and ignition systems of the vehicle, and means disposed exteriorly of the housing for actuating said secondary switch. 90
9. A safety device for automobiles comprising a housing having a movable door, a plurality of notched permutation discs carried by said door, an arm pivoted to the door, a locking bolt operably connected to said arm, a slideable tooth carried by said arm, said tooth being receivable in the notches of the discs and adapted to engage the edges of the discs, opposite lines of a circuit connected to said arm, a conducting piece attached to one of said lines and insulated from said arm a conducting strip secured to said arm and normally spaced from said piece a stem carried by the tooth and adapted to bring said strip into engagement with said piece, means carried by said arm for retaining said strip in engagement with the angle piece, a main two-way switch and a secondary two-way switch mounted in said housing, each switch including a pair of terminals and a switch arm, one of the terminals of the main switch being connected to the arm of the secondary switch, 95
- 30 the remaining terminal of the main switch being adapted for connection to a dash board switch, and the terminals of the secondary switch to the alarm and ignition systems of the vehicle, and means disposed exteriorly of the housing for actuating said secondary switch. 100
- 35 secured to said arm and normally spaced from said piece a stem carried by the tooth and adapted to bring said strip into engagement with said piece, a main two-way switch and a secondary two-way switch mounted in said housing, each switch including a pair of terminals and a switch arm, one of the terminals of the main switch being connected to the arm of the secondary switch, 105
- 40 the remaining terminal of the main switch being adapted for connection to a dash board switch, and the terminals of the secondary switch to the alarm and ignition systems of the vehicle, and means disposed exteriorly of the housing for actuating said secondary switch. 110
- 45 secured to said arm and normally spaced from said piece a stem carried by the tooth and adapted to bring said strip into engagement with said piece, a main two-way switch and a secondary two-way switch mounted in said housing, each switch including a pair of terminals and a switch arm, one of the terminals of the main switch being connected to the arm of the secondary switch, 115
- 50 the remaining terminal of the main switch being adapted for connection to a dash board switch, and the terminals of the secondary switch to the alarm and ignition systems of the vehicle, a pair of operating stems extending from the arms of the secondary switch, and means disposed exteriorly of said housing for engaging one of said stems. 120
10. A safety device for automobiles comprising a housing having a movable door, a plurality of notched permutation discs carried by said door, an arm pivoted to the door, a locking bolt operatively connected to said arm, a slideable tooth carried by said arm, said tooth being receivable in the notches of the discs and adapted to engage 125
- 60 a circuit connected to said arm, a conducting piece attached to one of said lines and insulated from said arm a conducting strip secured to said arm and normally spaced from said piece a stem carried by the tooth and adapted to bring said strip into engagement 130
- 65 notches of the discs and adapted to engage

with said piece, means carried by said arm for retaining said strip in engagement with the angle piece, a main two-way switch and a secondary two-way switch mounted in said housing, each switch including a pair of terminals and a switch arm, one of the terminals of the main switch being connected to the arm of the secondary switch, the remaining terminal of the main switch being adapted for connection to a dash board.

switch, and the terminals of the secondary switch to the alarm and ignition systems of the vehicle, a pair of operating stems extending from the arms of the secondary switch, and means disposed exteriorly of said housing for engaging one of said stems.

In witness whereof I have hereunto set my hand.

CAMILLE MAUBORGNE.
